— ATTORNEY

UNITED STATES PATENT OFFICE.

JOHN F. BERTRAM, OF ST. LOUIS, MISSOURI.

CHURN.

Application filed June 9, 1920. Serial No. 387,681.

To all whom it may concern:

Be it known that I, JOHN F. BERTRAM, a citizen of the United States, residing at St. Louis, in the county of St. Louis City and State of Missouri, have invented certain new and useful Improvements in Churns, of which the following is a specification.

This invention relates to new and useful improvements in churning and has for its primary object to provide an arrangement of dashers for quickly churning milk and forcing the butter globules toward the top of the churn; the various parts of the device being of simple construction and easily accessible and removable for cleaning whereby the churn may be maintained in a highly sanitary condition.

Another object of the invention is to provide means whereby the dashers are yieldably maintained in operative position whereby they may move vertically when occasion demands.

Another object of the invention is to provide a churn including receptacle and dashers and means for supporting and journaling the same within the receptacle.

Other objects and advantages of the invention will become apparent during the course of the following description.

In the accompanying drawings forming a part of the application and wherein like numerals are employed to designate like parts throughout the several views

Figure 1 is a front view of the invention.

Figure 2 is a vertical section taken on the line 2—2 of Figure 1.

Figure 3 is a top plan of the invention, and

Figure 4 is an enlarged perspective view of the device for supporting and journaling the dashers within the receptacle.

Referring to the drawings wherein for the purpose of illustration is shown the preferred embodiment of the invention, the numeral 5 designates a supporting frame which consists of a base 6 having corner standards 7 rising therefrom, two or which provide the front legs, while the rear leg 9 is provided by an upright engaging the rear edge of the base and adapted to rise a substantial distance thereabove. The sides and back of the supporting frame are provided with horizontal brace bars 10, the front of the supporting frame being left open in order that the receptacle 11 in which the milk

is churned may be readily removed and inserted into the frame.

A driving mechanism supporting frame 12 is hingedly connected to the rear uprights 7 and the under side of the frame is provided with four openings to receive upstanding lugs 13 on the upper ends of the uprights 7 whereby the driving mechanism supporting frame 12 may be properly positioned upon the supporting frame 5. A pair of transverse bars 14 are secured to the front and rear cross bars of the driving mechanism supporting frame and each is equipped with a bearing, as are the end bars of this frame in order that a driving shaft 16 may be journaled in the frame. Collars 17 are secured to this shaft on opposite sides of the bearings carried by the end bars of the frame and a crank handle 18 is provided for the shaft in order that the same may be manually operated. A pair of beveled gears 19 are keyed to the shaft to be disposed above the receptacle 11 when the driving mechanism frame is disposed in a closed position.

A pair of dashers 20 are provided to operate within the receptacle 11, and each consists of a vertically disposed shaft extended through an opening in the cover 21 of the receptacle. The other end of each shaft 85 adjacent its end is provided with a squared portion to receive thereon a beveled gear 22 for intermesh with the beveled gears 19, and the upper extremity of each shaft is reduced and round to be journaled in openings 90 in the bars 14. The lower ends of the dashers are also reduced in a similar manner to be inserted in openings 23 in a plate 24 which is positioned above the bottom of a glass receptacle 11. This spacing is accomplished 95 by providing the edges of the bottom of the receptacle with a rounded off formation so that opposite edges 25 of the plate 24 engage this rounded portion and therefor is supported slightly above the bottom of the 100 glass receptacle.

In order to quickly separate the fatty globules from the milk as it is being churned and force these globules to the upper portion of the receptacle, I provide each dasher 105 shaft with a pair or series of outwardly extending blades 26, the blades of each series being disposed vertically on the shaft and the two series being disposed in relative staggered relation. As clearly shown in 110

Figure 2 of the drawings, these blades are inclined and as seen in Figure 1 are disposed upon opposite sides of the dasher shaft. During operation of the churn, one series of blades on one dasher are adapted to cooperate with a similarly located series of blades on the coating dasher, the blades on the two dashers being inclined oppositely to one another whereby the fatty constituents in the milk are squeezed between the blades and forced upwardly of the receptacle. Further, as more clearly seen in Figure 1 the vertical edges of one series of plates on one dasher is adapted to cooperate with the vertical edges of the cooperating blades on the other dasher at the vertical center of the receptacle in order that the fatty globules containing butter may be broken up or separated from the milk.

In order that the driving mechanism frame 12 and consequently the dashers may be yieldingly supported or retained in an operative position, I secure one end of a coiled spring 27 to the driving mechanism supporting frame, while the opposite end of the spring is connected to a cord 28 or other like element, and a ring 29 associated therewith, whereby the spring may be tensioned when the above named frame is in operative position and the ring 29 associated with a stud or nail 30 secured in the base 6.

From the foregoing description it will be readily apparent that when it is desired to gain access to the receptacle, the driving mechanism frame 12 may be swung on its hinges to a vertical position after detaching the spring 27 from the base 6. This action will of course disengage the beveled gears 19 from those carried by the dashers, and of

course the top 21 of the receptacle may be readily removed so that the dashers may be readily accessible. After the dashers have been removed the plate 24 may also be removed and the receptacle and all parts may be thoroughly cleansed to maintain the same in a highly sanitary condition.

The foregoing description and the drawing has reference to the preferred or approved embodiment of the invention. It is to be understood, however, that certain changes in construction and arrangement of parts, materials, dimensions, etc., may be made as fall within the scope of the appended claim.

Having thus fully described my invention, what I claim as new and desire to secure by Letters Patent is:—

A churn comprising a supporting frame having sides to prevent lateral displacement of a receptacle placed within the frame, said frame having a side normally open through which the receptacle may be removed, a hinged cover for the frame for supporting a driving mechanism adapted to drive an agitating means placed in the receptacle, and a resilient member connected to said cover and adapted to be stretched across said open side of the frame to prevent accidental displacement of the receptacle through the open side of the frame and to retain the driving means in engagement with the agitating means.

In testimony whereof I affix my signature in presence of two witnesses.

JOHN F. BERTRAM.
